UNITED STATES PATENT OFFICE.

JOHN GREGORY AND VALENTINE LAPHAM, OF MARION, OHIO.

GRAIN-DRIER.

SPECIFICATION forming part of Letters Patent No. 288,428, dated November 13, 1883.

Application filed July 10, 1883. (Model.)

To all whom it may concern:

Be it known that we, JOHN GREGORY and VALENTINE LAPHAM, citizens of the United States, of Marion, in the county of Marion and State of Ohio, have invented certain new and useful Improvements in Grain-Driers; and we do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of our improved grain-drier. Fig. 2 is a longitudinal section of the same on line $x x$, Fig. 1. Fig. 3 is a cross-section. Fig. 4 is an elevation of one side of the machine, and Fig. 5 is a similar view of the other end.

Similar letters of reference indicate corresponding parts in all the figures.

Our invention has relation to that class of grain-driers in which the grain is carried through tubes inclosed in a heated casing by means of spirally-flanged conveyers, each tube connecting with the next; and it consists in the improved construction and combination of parts of the same, as hereinafter more fully described and claimed.

In the accompanying drawings, the letter A indicates a rectangular steam-tight metal casing adapted to be placed above a boiler of any construction, and having at its lower end an inlet-pipe, B, provided with a suitable stop-cock, and an outlet-cock, C, through which the air may pass out of the casing when steam is let into the same. The end pieces of the casing have a number of circular apertures, D, arranged in pairs, one above the other, to the edges of which apertures the ends of a number of cylindrical tubes, E, are fastened steam tight, so that the inside of the tubes may communicate with the outer atmosphere without allowing any of the steam to escape.

The ends of the tubes are provided at one end of the casing with T-shaped cross-pieces F, which leave the inner halves of the apertures open without any obstruction, while the outer halves of the apertures, across which the cross-pieces extend, are covered with semicircular pieces G, of perforated sheet metal or wire-cloth. The inner edges of the vertical heads

of the cross-pieces form flanges or ways H, between which the laterally-extending flanges I of a number of tapering spouts, J, of perforated sheet metal or wire-cloth, provided with handles for their convenient manipulation, fit and slide, which spouts connect each pair of tubes. The other end of the casing is provided with a rectangular frame, K, having a vertical cross-piece, L, which is secured to the end piece of the casing by means of bolts and nuts M, and the said frame has a cover, N, of perforated sheet metal or wire-cloth, which has rectangular apertures O, having frames P, connecting the lower half of one of each pair of tubes with one of the tubes of the pair below, and the upper and lower edges of the frames P form flanges or ways Q, between which ways the flanges of a number of spouts, R, of perforated sheet metal or wire-cloth, fit and slide.

The tubes are provided with shafts S, turning in bearings T in the heads of the cross-pieces at the one end of the tubes, and in the upper and lower ends of the frames P, and having spiral flanges U, the outer edges of which nearly touch the insides of the tubes, and which have means for rotating them, as shown in the drawings, where the ends of the shafts are provided with sprocket-wheels V, which are engaged by an endless sprocket-chain, W, passing over them and over a sprocket-wheel, X, upon the drive-shaft Y, which receives its motion from any appropriate motor.

The grain is fed into the machine through a tube, a, at the upper end of the casing, opening into one of the upper pair of tubes, and it escapes from the machine through a spout, b, at the lower end of the casing from the tube through which the grain passes last, and the feed-tube may be provided with a suitable slide, by means of which the flow of the grain may be regulated. The spiral flanges upon the shafts are wound thus, and the shafts revolved in such a manner that as the grain enters one of the upper pair of tubes through the spout or inlet-tube, the shaft, with its spiral flange, the capacity of the space between each turn of which is the same as the capacity of the feed-tube, will convey the grain to the other end, where the perforated spout will allow it to pass to the other tube of the same pair, where the conveyer will carry it to the other end, where the spout will allow it to

pass into the tube below, through which it passes into the one at the side of it, and so forth, until the grain passes out of the lower spout, from which the grain may be conveyed 5 to the bin or where it is desired to carry it. While the grain is passing through the machine, it comes in contact with the air at each end of the tubes passing through the perforated connecting-spouts, giving off its moisture, and becoming cooled off, the steam having been turned on at the commencement of the operation and the outlet-cock opened, allowing the air to escape, when it is again closed, the condensed steam passing out through the 15 inlet-cock into the inlet-pipe and down into the boiler, the drier being placed above the boiler, thus obviating the necessity of having an outlet-pipe for the condensed steam.

It follows that the machine may be used for 20 drying beans or any other product of similar character, and that the shafts may be revolved by means of cog-wheels meshing with each other, or by any other desired gear, without departing from the spirit of our invention.

Having thus described our invention, we 25 claim and desire to secure by Letters Patent of the United States—

1. The combination, in a grain-drier, of the outer casing, having steam-inlet and air-outlet cock at its lower end, the tubes passing 30 longitudinally through the casing in pairs connecting with each other, opening in the ends of the casing, and having perforated covers over the ends, and the spirally-flanged shafts 35 passing through the tubes and having means for revolving them, as and for the purpose shown and set forth.

2. The combination of the outer casing hav-

ing the steam-inlet and the air-outlet cock at its lower end, the tubes passing longitudinally 40 through the casing in pairs, having the perforated covers covering parts of the open ends of the same, and the perforated connecting-spouts connecting the several tubes consecutively, and the spirally-flanged shafts revolving 45 in the tubes, in the manner and for the purpose shown and set forth.

3. The herein-described grain-drier, consisting of the rectangular casing having the inlet-cock for steam and the air-outlet cock, the 50 tubes passing longitudinally through the casing in pairs and opening in the end pieces of the casing, the T-shaped cross-pieces forming bearings and ways, as described, the semicircular perforated covers, the rectangular frame 55 fastened to the end of the outer casing having the rectangular openings the ends of which form bearings and horizontal ways, as described, in its perforated cover, the perforated spouts sliding in the ways formed at both ends 60 of the tubes and connecting the tubes consecutively, the spirally-flanged shafts having means for revolving them in the tubes, and the grain-feeding tube entering the end of one of the upper pair of tubes, and the outlet-tube opening 65 from one of the lower pair of tubes, all constructed, combined, and arranged as and for the purpose shown and set forth.

In testimony that we claim the foregoing as our own we have hereunto affixed our signatures in presence of two witnesses.

JOHN GREGORY.
VALENTINE LAPHAM.
